UNITED STATES PATENT OFFICE

ROLLO MARPLE AND GEORGE B. ELY, OF CHARLOTTE, MICHIGAN, ASSIGNEES TO
HANCOCK MANUFACTURING CO., OF CHARLOTTE, MICHIGAN, A CORPORATION OF
MICHIGAN.

WINDOW-REGULATOR HANDLE.

Application filed February 3, 1926. Serial No. 85,653.

The invention pertains to a window regulating device and more particularly to the manufacture and assembly of a window regulator handle suitable for use in an enclosed automobile.

One object of our invention is to produce a handle in which simplicity of design and ease of assembly of the parts are salient features.

Another object of our invention is to provide a handle which, due to the ease with which each part may be produced from cold sheet or bar metal, is very economical to manufacture.

Another object is to provide a handle which will have sufficient strength to withstand great strain.

We have shown, in the following description and the accompanying drawings, a preferred embodiment of our invention, but the scope of our invention will be shown in the appended claims.

In the drawings:

Figure 1 is a longitudinal section of our handle completely assembled.

Fig. 2 is a plan view of our handle.

Fig. 3 is a longitudinal view of the shell having a part of the shell broken away.

Fig. 4 is a cross sectional view of the assembly taken on a line 4-4 of Fig. 2, showing the method of securing a supporting bar within a shell.

Our improved handle comprises generally an arm 3 having a tubular shank 4 at one end and a turn button or knob 5 at its other end. In its preferred form, we employ a member 6 in the form of an elongated rigid bar of substantially rectangular cross section having at one end an enlarged head 6^a adapted for connection with a part to be operated. Herein the head 6^a has an angular opening 7 therein into which an insert 8 is driven or otherwise rigidly secured therein so as to become in effect a part of the member 6. This insert 8 has in turn an aperture 9 adapted to receive a part (not shown) to which the rotational motion of the handle is to be transmitted. Both the insert 8 and the supporting bar 6 may be stamped or forged from cold rolled steel.

A covering shell 10 pressed or stamped from sheet metal, and having any desired design and finish, has relatively the same

shape and contour as the member 6 so as to fit snugly thereabout. The shell comprises 55 a front wall 11 and a peripheral edge wall 12. The member 6 fits into the covering shell 10 and is secured in place by turning over the edge of the peripheral wall to form an inturned flange 13 (Fig. 4) on the rear 60 side of the member 6. An enlarged opening 14 in the head of the shell is axially aligned with the aperture 9 in the insert 8.

The tubular shank 4 is in the form of a sheet metal stamping and is rigidly secured 65 at one end of the arm 3 at the rear side of the head 6^a and coaxially of the aperture 9. This is accomplished in the present instance by providing at the base of the shank an out-turned flange 16 entered between the 70 supporting bar 6 and the inturned flange 13 on the shell 10.

At the opposite end of the arm 3 is secured the finger-piece or knob 5. To this end I provide a pivot stud 17 which is inserted or otherwise secured to the member 6 and passes through the front wall 11 of the shell and projects a short distance therefrom. A bushing 18 is rotatably held on the stud 17 by a washer 19. The knob 5 is 80 made from sheet metal and comprises a tubular shank portion 20 and a cap portion 22. The shank portion fits tightly about the bushing 18, and its outer end flares outwardly to form an enlarged outer end 21. 85 Over this enlarged outer end 21 is fitted the cap 22 secured thereon by bending the peripheral edge of the cap inwardly into interlocking relation with the enlarged outer end as shown at 23.

It will be seen that our improved handle being composed of parts made from cold sheet or bar metal, and capable of quick and easy assembly, may be very economically manufactured. Also, it presents a neat and finished appearance, and possesses ample strength and rigidity.

We claim as our invention:

1. A handle of the character described comprising an elongated rigid member, a 100 covering shell of sheet metal fitting closely about said member, said rigid member being shaped to completely fill the interior of said shell, one end of the member having a transverse opening therein to receive a part to be 105 operated, and a tubular shank alined with

said opening and rigidly secured to the member and the other end of the member having a finger-piece thereon.

2. A handle of the character described comprising an elongated rigid member, a covering shell of sheet metal fitting closely about said member, one end of the member being enlarged to form a head and said head having an opening therein of substantial size with an apertured insert rigidly secured in said opening, and a tubular shank secured to one side of said head coaxially of the aperture therein, said shank being in the form of a sheet metal stamping formed independently of the shell.

3. A handle of the character described comprising a hollow shell formed from a flat sheet of metal and shaped to provide an elongated arm having a head at one end, a tubular shank secured at one side of said head and interengaging with said shell, and means for reinforcing said shell throughout the entire length thereof.

4. A handle of the character described comprising an arm having a head at one end adapted to receive a part to be operated, a finger-piece at the other end comprising two interfitting sections formed of sheet metal and a bushing enclosed in one of said sections and rigid therewith, and a pivot rigid with said arm for said bushing.

5. A handle of the character described comprising an arm having a head at one end adapted to receive a part to be operated, a finger piece at the other end comprising two interfitting sections formed of sheet metal, and means for rotatably mounting the finger-piece on the arm comprising a stud rigid with the arm and having a bushing rotatable thereon, one of said sections having a tubular portion in which said bushing is secured.

6. A handle of the character described comprising an operating arm having a stud rigidly secured near one end, a bushing rotatable on said stud, and a knob comprising two sections formed of sheet metal and secured together in interfitting relation, one of said sections constituting a tubular shank in which said bushing is secured and the other section constituting a cap for the shank section.

7. A handle of the character described comprising an elongated rigid member, a covering shell formed from a flat sheet of metal and fitting snugly about said member, said shell having a front wall and a peripheral edge wall with an inturned flange on the edge wall engaging the rear side of said rigid member, one end of said member having an enlarged opening therein with an apertured insert rigidly secured in said opening and adapted to receive a part to be operated, a tubular shank in the form of a metal stamping having at its base an out-turned flange entered between said member and the inturned flange of the shell so as to be rigidly secured to the member, a pivot stud rigidly secured in the opposite end of said member and passing through said shell on the side opposite said shank, a bushing rotatable on said stud and held against axial movement thereon, and a knob formed of sheet metal and mounted on said bushing, said knob comprising a tubular shank portion fitting tightly about said bushing and having an enlarged outer end, and a cap portion fitting over the enlarged outer end of the shank portion and bent into interlocking relation therewith.

In testimony whereof we have hereunto affixed our signatures.

ROLLO MARPLE.
GEORGE B. ELY.
